OSCILLATOR CIRCUIT

David Arthur Bell, Chelmsford, England, assignor
to Radio Corporation of America, a corpora-
tion of Delaware

Application February 18, 1938, Serial No. 191,156
In Great Britain March 6, 1937

3 Claims. (Cl. 250—36)

This invention relates to electron discharge device oscillation generators and more particularly to such generators of the kind in which regeneration is obtained by coupling between a tuned output circuit and an input circuit. The invention seeks to provide improved oscillation generators of the kind referred to which, although employing ordinary tuned circuits with coils of normal Q value, shall be of high stability, which shall 5 not be liable to change materially in frequency as a result of small changes in operating potentials or as a result of ageing of the electron discharge device, and whose frequency shall be very little affected by the harmonic components generated 10 in the electron discharge device.

According to this invention, an electron discharge device oscillation generator comprises in combination an electron discharge device, a circuit resonant to the desired frequency to be generated and energized from an output electrode of said device, means closely coupling said circuit to an oscillation input electrode of said device whereby a high degree of positive or regenerative 20 feed back for oscillation generation is obtained 25 and resistive means for applying a degree of negative or degenerative feed back to said device.

Preferably the resonant circuit is a parallel tuned circuit connected at one end to the output electrode of the electron discharge device and 30 coupled at the other to the oscillation input electrode thereof, an intermediate point thereon being connected, through a circuit including a resistive feed back impedance to a point which is at 35 cathode potential as regards the oscillation frequency, e. g., to earth or to the cathode itself.

By the expression "resistive" as herein employed in connection with the means providing degenerative feed back, is meant that the current through the impedance by means of which said feed back is obtained, is substantially in phase 40 with the voltage across said impedance, and that the ratio of said current to said voltage is independent or approximately independent of frequency.

The invention is illustrated in the accompanying diagrammatic drawing in which,

Figure 1 shows a circuit diagram of a preferred embodiment of the invention;

Fig. 2 shows a modification comprising a tuned 50 circuit made up of an inductance paralleled by two capacitors in series;

Fig. 3 shows another modification using in one 55 part of the circuit an inductance in series with a resistor having an inherent distributed capacitance; and

Fig. 4 shows still another modification in which a series combination of inductance, resistance, and distributed capacitance serve as a substantially pure resistance at the operational frequencies.

Referring to Fig. 1, which shows one way of carrying out the invention, a triode or other thermionic valve 1 has its anode 2 connected to its control grid 3 through a parallel tuned circuit in series with a coupling condenser 4 the said coupling condenser being adjacent the grid 3, and the said grid is connected to the cathode 5 through a grid leak 6. The tuned circuit is exemplified as consisting of an inductance 7 shunted by a fixed condenser 8 and by an ad- 15 justable condenser 9 and the valve 1 is shown as an indirectly heated cathode triode with the cathode heater 10 energized from a source 11 through a rheostat 12. If now an intermediate tap 13 on the inductance 7 of the tuned circuit 20 were connected merely through the usual anode potential source 14 (shunted by the usual condenser 15) to the cathode 5, the generator would be an ordinary well known generator having the well known defects of instability as regards frequency. In accordance with this invention, however, a resistance 16 is included in the lead between the intermediate tap 13 and the cathode 5. This resistance 16 provides resistive degenerative 25 or negative feed back and its provision enables 30 the control grid 3 to be closely coupled to the tuned circuits 7, 8, 9—as is desirable for stability of frequency—and also greatly reduces the generation of harmonic voltages of such phase as would tend to disturb the frequency of oscillation. 35 The circles V represent voltmeters.

In a practical example of generator as just described operating at a frequency of 80 kilocycles per second, the valve 1 was of the type now known under the trade designation Marconi 40 MH4; the tuned circuit consisted of an inductance 7 of 200 microhenries shunted by a total capacity (including stray capacity) of about 0.02 micro-farad; the coupling condenser 4 was of 0.15 micro-farad; the grid leak 6 was of one quarter 45 of a megohm; and the resistance 16 providing degenerative feed back was of 1,000 ohms.

Circuits as just described have been experimentally tested for working frequencies of 80 k. c. per second, 320 k. c. per second, and 560 k. c. 50 and have been found remarkably free from frequency deviation as a result of applied voltage variations. For example, in the 80 k. c. case, an increase in anode voltage from 115 to 237 volts produced a frequency increase of only 2 cycles per 55

million, while a variation of filament voltage from 2.5 to 4.42 (the normal voltage being 4) resulted in a frequency increase of 16 cycles per million. In the 320 k. c. case variations of anode voltage by 5 $\pm 11\%$ produced frequency changes, respectively, of -0.8 cycles per million and $+0.45$ cycles per million, variations of filament voltage of $\pm 10\%$ producing frequency changes, respectively, of $+0.6$ cycles per million and -0.6 cycles per million. In this connection it may be noted that 10 frequency changes due to variations (in the same direction) of anode and filament voltages are opposite in direction so that, in cases where these voltages are derived from a common source, a 15 very high degree of constancy should be obtained. For the 560 k. c. case variations of $\pm 12\%$ in anode voltage produced variations of about ± 5 cycles per million and variations of $\pm 10\%$ in filament voltage produced variations of about ± 4 cycles per million. Reduction of the harmonic 20 content is consequent upon the use of resistive negative feed back which, in particular, tends to suppress harmonic voltages of such phase relationship to the anode current of the valve as 25 would cause disturbance of the frequency of oscillation. Frequency variations due to grid current are minimized by the close coupling between tuned circuit and grid and for the same reason frequency variations due to variations in inter-electrode capacity of the valve can be greatly reduced. These are very important advantages.

In the modification shown in Fig. 2 the tuned circuit capacity is made up of two capacities 17, 18, in series, and instead of taking the tap to a point 13 on the inductance 7 of said circuit 7, 17, 18, the tap is taken to a point (here marked 13') between the two condensers 17, 18. In Fig. 2 the anode feed is shown applied via a choke 19 direct to the anode.

In some cases, especially where high frequencies are in question, distributed capacity across the degenerative feed back resistance may result in said feed back being insufficiently resistive in nature. In such a case either of the embodiments 45 already described may be modified by connecting an inductance in series with the resistance. In practice the reactance of this inductance is small compared to its ohmic resistance so that the required value of inductance is approximately CR^2 50 where C is the distributed capacity measured in farads across the resistance and R the resistance in ohms and the inductance is measured in henrys. Fig. 3 shows the circuit of Fig. 1 modified in this way, 20 being the series inductance, and the broken line condenser 21 represents the distributed 55 capacitance across the resistance 16. Such a series combination of inductance 20, resistance 16, and (distributed) shunt capacity 21 will act as a substantially pure resistance for all values of 60 frequency such that $p^2C^2R^2$ is negligible compared to unity,

$$\left(\frac{p}{2\pi}\right) \text{ is the frequency}$$

Similarly, where the resistance element presents an undesirable amount of inductance (this difficulty may arise at low frequencies) a network consisting of a series branch of inductance and resistance shunted by a series branch of capacity and resistance may be employed (in place of a simple resistance 16) as a complex network of resistive nature for providing the degenerative feed back. Fig. 4 shows the circuit of Fig. 1 modified in this manner, the network comprising a 10 branch consisting of resistance 22 and series inductance 23 shunted by a branch consisting of resistance 24 and series capacity 25.

It will be seen that in the illustrated arrangements close coupling to the grid 3 is effected by 15 choosing the value of the coupling condenser 4 to be of low impedance at the oscillation frequency while the coupling of the anode and grid to the tuned circuit may be so chosen that the effects of space charge variations in the valve upon the frequency generated substantially cancel 20 out, leaving substantial immunity from frequency variations from this cause.

I claim:

1. A device for canceling out the effects of space 25 charge variations in the discharge tube of an oscillation generator, said tube comprising a cathode, an anode, and a grid; said device including a resonant circuit interconnecting the cathode and anode, a regenerative feed-back circuit to said grid from a suitable point on said resonant 30 circuit, and means for degeneratively coupling said anode and grid comprising impedance means connecting said cathode to an intermediate point in the capacitive leg of said resonant circuit.

2. An oscillation generator comprising an electron discharge tube having at least a cathode, an anode and a control grid, a parallel resonant circuit connected at one end to the anode and having close coupling means at the other end for supplying regenerative feed-back energy to said control grid, and means to stabilize the frequency of the oscillations generated, said means being constituted by a substantially pure resistance in series with a coupling capacitor and in circuit between the cathode and an intermediate point in 45 the capacitive leg of said parallel resonant circuit.

3. An oscillation generator comprising an electron discharge tube having at least a cathode, an anode and a control grid, a parallel resonant circuit formed by an inductance and two serially 50 connected capacitors, a conductive connection from the anode to one end of said resonant circuit, a capacitor for closely coupling the other end of said resonant circuit to the control grid and for supplying the same with regenerative feed-back energy, and a degenerative feed-back circuit constituted by a substantially pure resistance connected to the junction between said two serially connected capacitors and coupled to the cathode.

DAVID ARTHUR BELL.
